(57) **CLAIM**

The ornamental design for a slot track, as shown and described.

DESCRIPTION

FIG. 1 is a front perspective view of the design of the present invention;

FIG. 2 is a rear perspective view thereof;

FIG. 3 is a front view thereof;

FIG. 4 is an enlarged section of the front view of FIG. 3;

FIG. 5 is back view thereof;

FIG. 6 is an enlarged section of the back view of FIG. 4;

FIG. 7 is a left side view thereof;

FIG. 8 is a right side view thereof;

FIG. 9 is a top view thereof;

FIG. 10 is an enlarged section of the top view of FIG. 9;

FIG. 11 is a bottom view thereof; and,

FIG. 12 is an enlarged section of the bottom view of FIG. 11.
